UNITED STATES PATENT OFFICE.

JOHN HERRICHT, OF CLEVELAND, OHIO.

ELECTRIC-ARC LAMP.

SPECIFICATION forming part of Letters Patent No. 674,338, dated May 14, 1901.

Application filed August 27, 1900. Serial No. 28,184. (No model.)

To all whom it may concern:

Be it known that I, JOHN HERRICHT, a citizen of the United States, residing at Cleveland, in the county of Cuyahoga and State of Ohio, have invented certain new and useful Improvements in Arc-Lamps; and I do hereby declare the following to be a full, clear, and exact description of the invention, such as will enable others skilled in the art to which it applies to make and use the same, reference being had to the accompanying drawings, and to figures of reference marked thereon, which form a part of this specification.

My invention relates to arc-lamps, and has for its object the provision of simple and effective means for regulating the length of arc to be struck, together with a new form of clutch mechanism for controlling and lifting the upper carbon during the striking of the arc, designed to obviate the use of a dash-pot for taking up the shock at the end of the armature travel, and other details of construction which combine to produce a cheap and durable lamp, reliable in its operation and easy to trim.

Referring to the drawings, in which like parts are similarly designated, Figure 1 is a section of my improved lamp; Fig. 2, a modification of the carbon-lifting mechanism and regulator for determining the length of arc to be struck; and Fig. 3 is a view, partly in section, of the inner globe or "bottle-bracket."

The solenoid (indicated by 10) is provided with an iron conical upper head 11, screwed or otherwise adjustably secured to the brass body 12, and a flat lower head 13, somewhat longer in diameter than the upper head and against which the case (not shown) fits tightly, effectually preventing hot air from the arc from entering said case and burning the insulator on the windings of the spool. I preferably make the lower head of the spool of non-magnetic material, as this has an advantage in reducing the heating of the spool and besides prevents the concentration of the magnetism at this point and allows the armature to have an easy upward movement.

It will be observed that I have shown the conical and tapered head 11 as screwed on the body, so as to permit the increasing or decreasing of the distance apart of the two heads and allow a greater or less number of wind-

ings to be placed thereon, so that one structure will suffice for lamps to be wound for one hundred and ten, two hundred and twenty, and five hundred volts, while the conicity of the head gives a very satisfactory working variation in the magnetism, which is greatest at the upper head.

Screwed or otherwise adjustably held in the upper end of the brass body 12 is the iron core 14, which is made adjustable therein for permitting a longer throw of the armature for different-sized arcs, and in this core is screwed or otherwise adjustably held an iron upper-carbon guide-tube 16, preferably projecting some distance through the core 14 and provided with a lateral slot 17, in which the wire connected to the carbon-terminal has free motion during the feeding and adjustment of the carbon. I make this tube of iron and carry it below the upper magnet-head, so that when the solenoid is energized said tube will have a braking effect on the armature to aid in preventing the latter from being carried up so far as to touch the core, and when properly adjusted it will act on the armature and its gripped carbon to give it a slight up-and-down swing when first lifted and then gradually permit it to move down. I have described this tube as made of iron, but it may be made of brass when it is desired to do away with its braking action. In this tube is the carbon cap or terminal, comprising a split socket 53, fitting the end of the carbon and provided with a ball-and-socket joint 54 and a stirrup 55, sufficiently thick to prevent it from passing through the slot, and in which the terminal wire is twisted. This mode of structure allows free turning of the carbon and decreases the wear on the wire sliding in the slot.

The tubular armature 18 has vertical motion in the magnet-body 12 and has secured to its lower end a guide-tube 19, having a slot 20 cut therein, through which the clutch can grip the upper carbon. Although I have shown but one slot and clutch, it is obvious that I may make them in pairs.

Secured to the armature and moving with its guide-tube 15 is a pair of springs 21 22, preferably, though not necessarily, made of phosphor-bronze, bent inwardly, so as to bear one against the tube 19 and the other against the carbon, the free ends being then bent out-

wardly. I have shown one of these springs 21 provided with a jaw 23 at its bend, said jaw passing through the slot 20 in the guide-tube 19 to grip the carbon with its arcuate face. The outwardly-bent ends of these two springs are guided in and project through the slots 15 in the prolonged spool-body 12, and on this prolonged threaded end I screw a regulator 24, having conical or flaring inner faces, against which the ends of the springs 21 22, projecting through the slot 15, slide. By adjusting this regulator along the length of the tube I can adjust the length of arc struck and vary the tension of the springs in accordance with the strength of the magnet, and when drawn up gradually take up the shock when the armature is attracted, obtaining a better and more reliable action than with the use of a dash-pot. The relative form of the outwardly-bent portions of the springs 24 is such that when the carbon has been lifted to near its limit the springs will be at their dead-point—that is, not have any tendency to draw the carbon down, but will be pulled below the dead-point only by the weight of the carbon, and thus bring the springs in position to draw the carbon down.

It will be observed that I have shown attached to the outwardly-pressing spring 21, which carries the clutch-dog, an almost straight inwardly-pressing spring 25, bent outwardly at its lower end, acting as a stop for the armature and at the same time aiding in releasing the spring-held dog 23. However, this may be dispensed with, as the action of the springs 21 22 has proven to be always certain.

Below the lower position of the springs 21 22 and on the tube 19 I screw a nut 26, which may also act as a spreader for said springs 21 22, or said springs may be prolonged to impinge on and be spread by the heat-shield 27, which latter is insulated from and held between the nut 26 above and a similar nut 28 below it, both screwed on the brass tube 12.

Closing the bottom of the brass tube is the plate 29, having a central tubular boss 30, which acts to trip spring 25, the lower surface of this closure acting as a top cap for the inner globe or "bottle" and an adjustable lower limit for the armature.

The heat-shield 27 is connected to the outer globe-support 9, which consists of the usual rim, to which is secured a pair of oppositely-disposed locking-pieces taking over a flange 32 on the heat-shield. These locking-pieces are guided in radial slots 33 in the globe-ring and are themselves provided with slots (shown in dotted lines) in which are retaining-screws 34, on which the locking-pieces have radial motion. Stationary screws 35 and lock-nuts 36 serve to hold the devices in operative position, while the finger-grips 37 allow the trimmer to pull them outward, release the nose 38 from the flange 32; and remove the outer globe with its retaining-ring attached.

Depending from the heat-shield 27 is a rod

39, having negative terminal nuts 40 and provided with a slot 41, ending in a circumferential groove 42 near the lower end of said rod, the shoulders at the junction of said groove and slot being beveled or rounded, as shown at 43. Over this rod slides a tube 44, carrying at its lower end a bracket 45. In the upper end of this tube I secure a thumb-screw 46, provided with a collar 47, which abuts in its outward movement against one or two retaining-pins 48 to prevent the trimmer from unscrewing it too far.

The bracket is provided with a socket 49, carrying at its center a thumb-screw-adjusted lower-carbon holder 50. In the bottom of the socket is placed the usual air-tight packing 51, upon which the lower end of the bottle rests. These bottles or inner globes often crack from the excessive heat, and I have found that this is due to their being unable to expand when held in place by the usual thumb-screws 8, and to obviate this I place between said screws and the lower grooved part of the bottle a thin sheet of sheet metal 52, which may have one or more turns, and which is so thin that when the thumb-screws are screwed in it will partly conform to the outline of the lower part of the bottle, yet not fit close thereto over the entire surface, thus allowing the metal strip to give when the bottle expands. This means of holding the end of a bottle is cheaper than springs, more easily inserted, readily replaced, and reliable in its action.

Fig. 2 shows a modified form in which the spool-body 12 has an iron head 56, formed in one piece with the core 57, and a brass carbon-guide which passes through the latter, all secured together by screws 58. The lower spool-head 13 is secured as before described; but instead of prolonging the spool-body I secure to its end a conical or flaring piece 59, provided with a flange 60, said conical piece threaded from the flange to its lower end, said conical guide-piece being a substitute and equivalent in its action to the ring-regulator 24, Fig. 1. Between the flange 60 and a ring 61 is held the heat-shield 27. The armature 62 is tubular and provided at its upper end with a brass stop 63, which may be screwed therein to permit adjustment, if desired, and has slots in its lower end, in which are secured leaf-springs 64 65. The spring 65 has its lower end 66 bent upward or reverted to bear against the back of the spring 67, that carries the clutch 68, said spring 67 being prolonged to abut against the regulator 69, which is adjustable on the lower end of the conical portion 59 and forms the upper cap for the bottle, its lower face being provided with a centering-flange 70 for the bottle, and the upper face of said regulator carries a boss 71, designed to act on the spring 67 and release the clutch. This clutch passes through a slot 72 in the tube 19, threaded in the lower end of the armature.

The operation will be as follows: Circuit

being made in the position shown in Fig. 1, the solenoid is energized, the armature 18 attracted by the core 14, and being resisted in its motion as soon as the upper end thereof has passed the lower end of the tube 16 by the magnetism engendered in said portion of the tube. At the same time the springs 21 22 slide over the conical or flaring surfaces of the regulator, are forced inward, grip the carbon with increasing strength, and exert an increasing resistance to the rise of the armature, which is then forced back to proper striking distance by said springs. For adjusting the lower limit of travel of the armature the top plate for the bottle 29 can be screwed up or down on the lower projecting end of the spool-body, while the upper limit of travel is similarly adjusted by moving the core 14, with or without the carbon guide-tube 16, as desired, while the clutch is adjustable by means of the regulator 24. In trimming the lock-nuts are loosened, and the trimmer by taking hold of the finger-grips 37 and drawing out the clamps and allowing the outer globe and retaining-ring to drop and hang by the chains which are attached at one end to the case (not shown) and at the other to said retaining-ring has free access to the inner globe. The thumb-screw 46 on the bracket is then loosened and is prevented from being drawn out of the slot 41 in the rod 39 by reason of the collar 47 abutting against the pins 48. This allows the tube 44 to drop straight down, being guided by the screw 46, that slides in the slot and enters the circumferential groove 42. The bracket with the bottle attached can now be swung around and the lamp conveniently trimmed. In this form in order to adjust the grip-regulator it will be necessary for the trimmer to open the case; but in the form shown in Fig. 2 this will not be necessary, as everything is accessible from the outside and below the heat-shield. It will be observed that in this modification the armature and the parts carried thereby are free to rotate as well as the carbon.

Having thus described my invention, what I claim as new therein, and desire to secure by Letters Patent, is—

1. In an arc-lamp, a solenoid comprising a non-magnetic body and lower head, an upper head of magnetic material adjustable on the body, and a core adjustable within the upper end of said body, substantially as set forth.
2. In an arc-lamp, a solenoid comprising a non-magnetic body and lower head, a conical upper head of magnetic material adjustably mounted on, and a core adjustably mounted in said body, in combination with a carbon-tube adjustably secured within said core, substantially as set forth.
3. In an arc-lamp, a solenoid comprising a non-magnetic body and lower head, a conical upper head of magnetic material adjustably mounted on, and a tubular core adjustably

mounted in the upper end of said body; in combination with a carbon guide-tube of magnetic material adjustable in and whose lower end projects below said core, substantially as set forth.

4. In an arc-lamp, a solenoid, the body thereof projecting below the lower solenoid-head and threaded, in combination with a ring adjustable on said threaded portion and having a substantially conical bearing-surface, an armature sliding in said body, springs attached to the armature whose free ends slide against the bearing-surface of the ring, substantially as set forth.

5. In an arc-lamp, a solenoid, a conical or flared bored tube secured to the end of the spool-body of the solenoid; in combination with an armature sliding in said body, springs secured thereto and arranged to bear against the conical walls of the extended body of the armature, substantially as described.

6. In an arc-lamp, a solenoid, the body thereof extending below the lower solenoid-head and exteriorly threaded; in combination with a ring in the threaded portion, a tubular armature-spring secured thereto, a bend in said spring arranged to grip the carbon, the free ends of said spring engaging the ring, and means for spreading said springs at the lower limit of their travel, substantially as set forth.

7. In an arc-lamp, a solenoid, the body thereof extended below the lower solenoid-head and in combination with a tubular armature, springs thereon arranged to grip the carbon, means for gradually increasing the tension of said springs during their upward travel and means for spreading the springs at the end of their drop, substantially as and for the purpose set forth.

8. In an arc-lamp, a solenoid, the body thereof extended below the lower solenoid-head slotted and threaded; in combination with a tubular armature, a guide-tube secured in the lower end thereof, springs secured to a moving part and provided with a bend, the bend of one of said springs engaging the upper carbon, means adjustable on said extension for graduating and regulating the tension of said springs, a spreader also adjustable thereon, means for limiting the drop of the armature and for positively releasing the clutch, substantially as and for the purpose set forth.

9. In an arc-lamp, a solenoid, the body thereof extended below the lower solenoid-head and threaded, in combination with a tubular armature, springs secured thereto, one of which is bent to form a clutch, a stop secured to the spring-clutch, a plate adjustable and closing the lower end of the spool-body limiting the drop of the armature and organized to positively release the clutch, substantially as set forth.

10. In an arc-lamp, a solenoid, a conical extension secured to the end of the spool-body thereof, an external flange on said ex-

4

tension; in combination with a tubular armature, a spring-clutch attached thereto for lifting the carbon, springs arranged to slide on the conical bore in said extension, one of 5 said springs having its free end reverted to press the spring-clutch, and means for positively releasing the clutch, substantially as set forth.

11. In an arc-lamp, a solenoid, an extension 10 having a conical bore secured to the end of the spool-body thereof, a flange on said extension, means for securing the heat-shield against said flange, a plate having a central carbon-passage closing and adjustable on the 15 end of said extension and forming the bottle-cap, substantially as and for the purpose set forth.

12. In an arc-lamp, a solenoid, an extension having a conical bore and secured to the end 20 of the solenoid spool-body, in combination with a tubular armature, springs secured thereto at one end and organized to bear against the conical walls of the extension, a spring-clutch engaging the carbon and secured 25 to the armature, said armature and attached parts free to move vertically and to rotate, and means to positively move the spring-clutch out of engagement with the carbon whatever the degree of rotation, substantially 30 as set forth.

13. In an arc-lamp, a solenoid, the spool-body thereof extended below the lower solenoid-head and threaded, a stop on the exterior of said extended portion, means for 35 securing a heat-shield against said stop, a longitudinally-slotted rod depending from said heat-shield, a tube sliding on said rod carrying a bottle-bracket, and means for guiding the tube while sliding on said rod organized to allow revolution of the bottle at the 40 limit of drop, substantially as set forth.

14. In combination with an arc-lamp, a depending terminal rod, a longitudinal slot cut 45 therein, a circumferential groove cut at the end of said slot, a tube telescoping said rod and carrying a bottle-bracket, a thumb-screw in said tube and entering said slot and guiding the tube during its drop and limiting it at the groove, substantially as set forth.

15. In combination with an arc-lamp, a depending negative terminal rod, a longitudinal slot therein, a circumferential groove at the end of said slot, said slot having rounded shoulders where it enters the groove, a tube 55 telescoping on said rod, a thumb-screw limited in its outward movement engaging said slot and securing the tube to said rod and designed to enter the circumferential groove at the end of said slot, substantially as set forth.

16. The combination with an arc-lamp and bottle-bracket, of a socket for the bottle, retaining-screws therein and a sheet-metal strip between said screws and the foot of the bot- 65 tle, for the purpose set forth.

17. The combination with an arc-lamp and

bottle-bracket, of a socket on said bracket, a loose sheet-metal lining therefor, and retaining-screws arranged to force the sheet-metal lining against the bottle, substantially as and 70 for the purposes set forth.

18. The combination with an arc-lamp, of a heat-shield vertically adjustable and secured thereto, a flange on the heat-shield, a globe-supporting ring, devices radially slide- 75 able in said ring and arranged to secure the ring to said flange, and means for locking the devices in closed position, substantially as set forth.

19. The combination with an arc-lamp and 80 an adjustable heat-shield, of a flange on said shield, a globe-ring radially slotted, locking-pieces slotted and slideable in said slots and resting on the upper face of the flange, screws 85 passing through the slots in the locking-pieces, and means for securing the locking devices in closed position, substantially as and for the purposes set forth.

20. In an arc-lamp, in combination with the solenoid and its core, of a carbon guide-tube 90 of magnetic material adjustably secured in said core, substantially as set forth.

21. In an arc-lamp, a solenoid comprising a non-magnetic body and lower head, and a conical upper head adjustable on said body, 95 in combination with an armature shorter than the distance between the heads, substantially as set forth.

22. In an arc-lamp, a solenoid, an armature slideable therein, springs on said armature projecting below the lower solenoid-head, a substantially conical or flaring surface secured to the spool said springs organized to bear against said surface, substantially as set forth. 105

23. In an arc-lamp, a solenoid, a substantially conical guide-piece below the solenoid, an armature slideable in the solenoid; a pair of springs secured to and organized to resist the rise of said armature and bear against 110 said guide-piece, and constructed to grip and to release the carbon, substantially as set forth.

24. In an arc-lamp, a solenoid, a substantially conical guide-piece below the solenoid, 115 an armature slideable in the solenoid, a tension-spring and a carbon-gripping spring secured to said armature, both bearing on the inner conical surface of the guide-piece, and adjustable means for positively releasing the 120 carbon from said springs, substantially as set forth.

25. In an arc-lamp, a solenoid, a substantially conical guide-piece below the solenoid and held to a part thereof, an armature slide- 125 able in the solenoid, a pair of outwardly-spreading springs secured to said armature, one of said springs forming a carbon-grip, and both organized to slide on the conical surface, and means for preventing the rotation of the 130 armature during its vertical movement, substantially as set forth.

26. In an arc-lamp, a solenoid, an extension of the solenoid-body below the lower solenoid-head, in combination with an armature, a carbon-clutch and springs secured to said armature and coöperating with the extension of the solenoid-body to operate the clutch, substantially as set forth.

27. In combination with an arc-lamp and bottle-bracket, of a socket for the bottle, retaining-screws therein and a coil of sheet

metal between said screws and the foot of the bottle, for the purpose set forth.

In testimony that I claim the foregoing as my invention I have signed my name in presence of two subscribing witnesses.

JOHN HERRICHT.
